Primary Examiner — Steven J Czyz

(74) Attorney, Agent, or Firm — Norton Rose Fulbright
Canada(57) **CLAIM**

The ornamental design for the display table for hockey sticks, as shown and described.

DESCRIPTION

FIG. 1 is a perspective view of the display table for hockey sticks according to my new design, shown with hockey sticks mounted thereto;

FIG. 2 is front elevation view thereof;

FIG. 3 is rear elevation view thereof;

FIG. 4 is a right side elevation view thereof;

FIG. 5 is left side elevation view thereof;

FIG. 6 is a top plan view thereof; and,

FIG. 7 is a bottom plan view thereof.

The portions shown in broken lines do not form part of the claimed design.
